UNITED STATES PATENT OFFICE.

VICTOR E. CHAMBERLIN, OF INDIANAPOLIS, INDIANA, ASSIGNOR TO POPE MANUFACTURING COMPANY, OF JERSEY CITY, NEW JERSEY, A CORPORATION OF NEW JERSEY.

CONTROLLING DEVICE FOR MOTOR-VEHICLES.

No. 800,843.

Specification of Letters Patent.

Patented Oct. 3, 1905.

Application filed March 17, 1905. Serial No. 250,520.

To all whom it may concern:

Be it known that I, VICTOR E. CHAMBERLIN, a citizen of the United States, residing at No. 2128 Bellefontaine street, in the city of Indianapolis, in the county of Marion, in the State of Indiana, have invented certain new and useful Improvements in Controlling Devices for Motor-Vehicles, of which the following is a specification, reference being had to the accompanying drawings, forming a part hereof.

This invention relates to means for controlling the speed and direction of movement of motor-vehicles, and is more particularly concerned with the means for controlling the speed and direction of movement of electrically-propelled vehicles.

In the drawings, Figure 1 is a view in side elevation, partly broken out, of a sufficient portion of an electrically-propelled motor-vehicle to illustrate the application of the present invention thereto. Fig. 2 is a view in front elevation and on a larger scale of the controlling devices, the controlling lever or handle being broken off. Fig. 3 is a plan view of the parts shown in Fig. 2. Fig. 4 is an end view of the parts shown in Figs. 2 and 3. Fig. 5 is a diagrammatic view illustrating the arrangement and connection of the controller-contacts. Fig. 6 is a diagrammatic view illustrating the electrical connections of the fixed controller-contacts to the various generating, measuring, and translating devices. Fig. 7 is a diagrammatic representation of the windings of the motor shown in Fig. 6.

The vehicle to which the invention is applied may be of any usual or suitable construction, and, as shown in Fig. 1, it comprises a suitable battery-receiving body *a*, supported upon driving-wheels *b* and steering-wheels *c*, the body being provided with a steering-handle *d*, suitably connected to the steering-wheels, and with a controller *e*, suitably and conveniently placed with respect to the vehicle-seat, being secured, as shown in the present instance, to a vertical partition or support *e'* beneath the seat, while the handle *e* thereof projects upwardly through or at the end of the seat in a position convenient for manipulation. As shown more clearly in Figs. 2 and 3, the controller handle or lever *e* projects through a guard-plate *f*, having therein a bi-

furcated slot for the direction of the movements of the lever. When the vehicle is at rest, the controlling-lever stands in its normal position against the stop *f'*. For the several forward speeds the controlling-lever is moved forward from this normal position (indicated in full lines in Fig. 4) through the slot *f*². For the several speeds backward the lever is first moved laterally outward or away from the operator and is then moved backward through the slot *f*³. For the application of the electric brake the controlling-lever is first moved laterally inward or toward the operator and is then moved backward in the slot *f*⁴. Two springs *f*⁵ (shown in dotted lines in Fig. 2) are provided to bear upon the controller-handle when it is in its normal or "off" position and to retain it in line with the slot *f*² against accidental movement from one side to the other, but yielding in one direction or the other to permit lateral movement of the lever, as required. The guard-plate or lever-housing *f* is also provided, as at *f*⁶, with a seat for the reception of a bodily-removable emergency or safety-plug switch, (indicated at *f*⁷.) The location of this plug-switch in the lever-housing in immediate proximity to the controller-handle is most convenient for the operator.

The controller-handle *e* is arranged to operate the controller drum or cylinder through any convenient means. As represented in the drawings it is carried by a shaft *g*, being pivoted, as at *e*⁸, between two cheek-pieces *e*⁹, which are fixed to the shaft *g*. This arrangement permits the controller-handle to have the lateral movement which is desired in order that it may be moved into one or another of the slots in the lever-housing, which forms a directing and locking means for the lever. The shaft *g* is suitably supported in bearings on the frame of the controller and carries a gear-segment *g*', which engages a pinion *h*', mounted on the shaft of the controller drum or cylinder *h*. The latter is mounted in suitable bearings carried by the frame of the controller and is provided in any usual or convenient manner with a series of contacts *h*' *h*² *h*³ *h*⁴ *h*⁵ *h*⁶ *h*⁷ *h*⁸, which are diagrammatically illustrated in Figs. 5 to 12, inclusive. The contacts of the drum coöperate with a series of fixed contacts *m*' *m*² *m*³ *m*⁴ *m*⁵ *m*⁶ *m*⁷ *m*⁸ in a usual manner to effect certain electrical connections between the source of elec-

trical energy and the translating devices, as will be explained more fully hereinafter. A notched wheel h^2 , secured to the controller-drum h and coöperating with a spring h^3 , secured to the frame of the controller in the usual manner, insures a step-by-step movement of the controller.

The various connections effected by the movement of the controller will be readily understood upon reference to Figs. 5, 6, and 7, in which such connections are represented diagrammatically, it being understood that Fig. 5 illustrates the groupings of the contacts carried by the controller-drum. To avoid undue enlargement of this description, the several contacts on the drum will be referred to hereinafter and also designated by reference-letters as if they were members of but one group, although reference will be made to the several positions, which will clearly indicate the groups referred to. The fixed contacts m' , m^2 , &c., are severally connected to the source of energy and the various translating devices, as clearly indicated in Fig. 6, in which it clearly appears that the contact m' is connected to the positive charging terminal or terminals n' and through the removable emergency-plug f^7 and the armature o' of the motor o with the contact m^8 . The contact m' is also connected with the contact m^2 through a suitable resistance r . The contact m^3 is connected with the positive terminal of the storage battery B. The contact m^4 is connected with the negative charging terminal or terminals n^2 and with the negative terminal of the battery B and through one of the fields o^2 of the motor o with contact m^6 . Contact m^5 is connected through one of the fields o^3 with the contact m^7 . The ammeter-shunt of the usual voltammeter p may be connected in between the contact m' and the motor o , and the voltmeter leads into the battery connection through the contacts m^8 , m^4 . Lights, as at s , s' , and an electric alarm, as at t , may be connected into the battery-circuit through suitable controlling devices.

Referring now to the contacts on the controller-drum and assuming that the controller-handle is in its normal or off position, as indicated in full lines in Fig. 4, it will be observed that the contacts k' and k^3 , constituting this group, are connected so that the circuit between the battery and the motor is broken and the resistance between the contacts m' and m^2 is short-circuited, so that the proper connections are made for charging the battery. In the group of contacts for the first speed forward, which are brought into electric connection with the stationary contacts m' , &c., upon the first movement of the handle e^2 in the forward direction, the contacts k^2 and k^3 , k^5 and k^6 , and k^7 and k^8 are connected in pairs, as indicated, so that the battery, motor-fields, armature, and resistance are connected in series, whereby the voltage is low-

ered, and the vehicle is started at its slow speed. The next forward movement of the controller-handle brings the next or second speed group of contacts into electric connection with the fixed contacts m' , &c., and as contact k' is connected with contact k^3 , while contacts k^5 and k^6 and contacts k^7 and k^8 are connected in pairs, as before, the battery, motor-fields, and armature are connected in series with the resistance cut out, so that the armature and fields receive the full battery-voltage, and a higher speed in a forward direction is secured. The final movement of the controller-handle in the forward direction brings the contacts of the third speed group into connection with the fixed contacts, and as contacts k' and k^3 , contacts k^4 and k^5 , and contacts k^6 , k^7 , and k^8 are connected, as indicated, the battery and armature will be connected in series with the motor-fields in parallel, so that the field strength is weakened and a higher speed attained.

If the vehicle be coasting with the controller-handle in its normal or off position and it be desired to apply an electrical brake—that is, to cause the motor to be short-circuited through the resistance, whereby the energy developed by the rotating motor is transformed into heat—the controller-handle is first moved laterally inward or toward the operator and then backward in the slot f^4 . In the braking group of contacts thus brought into operative relation with the contacts m' , &c., contacts k^2 , k^7 , and k^8 are connected, and contacts k^5 , k^4 , and k^6 are connected, so that the motor-fields are connected in parallel and reversed, while the armature and resistance are connected in series. The motor is then driven as a dynamo, and the current generated is short-circuited through the resistance and is transformed into heat, retarding the speed of the vehicle. If the controller-handle be moved from its normal or off position first outward or away from the operator and then backward, the "first reverse" line of contacts will be brought into operative relation with the fixed contacts, and as contact k^2 is connected with contact k^7 , contact k^3 with contact k^8 , and contact k^5 with contact k^6 the armature connections are reversed and the battery, motor-fields, and resistance are connected in series, yielding slow rotation in backward direction. A further backward movement of the controller-handle e^2 in the slot f^3 brings the last set of contacts into operative relation with the fixed contacts, with the relations established as just described, except that the contact k' is directly connected with the contact k^7 and the resistance is cut out, thereby yielding a higher speed backward. It will be obvious that the contacts may be arranged in any desired relation and that all of the various speed and other conditions are secured by movement of the single controller-handle e^2 in the proper direction.

The arrangement shown and described herein, however, is most convenient in practical use, since movement of the controller-handle forward from its normal or off position first starts the vehicle forward at its slowest speed and then yields higher speeds in succession, while movement of the same controller-handle from its initial or off position backward either brings the electrical brake into operation or causes the vehicle to move backward, according to the lateral movement of the lever in one direction or the other before the backward movement thereof is begun.

15 I claim as my invention—

1. In a motor-vehicle, the combination of a motor, a controller therefor comprising a plurality of groups of contacts and connections to determine the speed and direction of movement of the motor, a controller-handle movable laterally and forward and backward, and a spring bearing upon said handle to retain it in line for movement in a fore-and-aft direction and yielding to permit lateral movement, substantially as described.

2. In a motor-vehicle, the combination of a motor, a controller therefor comprising a plurality of groups of contacts and connections to determine the speed and direction of movement of the motor, a controller-handle movable laterally and forward and backward, a housing having a bifurcated slot to guide the controller-handle, and a spring bearing

upon said handle to retain it in line for movement in a fore-and-aft direction and yielding to prevent lateral movement, substantially as described.

3. In a motor-vehicle, the combination of a motor, a controller therefor comprising a plurality of groups of contacts and connections to determine the speed and direction of movement of the motor, a controller-handle movable laterally and forward and backward, and stationary springs bearing upon opposite sides of said handle to retain it in line for movement in a fore-and-aft direction and yielding to permit lateral movement in either direction, substantially as described.

4. In a motor-vehicle, the combination of a motor, a controller therefor comprising a plurality of groups of contacts and connections to determine the speed and direction of movement of the motor, a controller-handle for said motor, a housing slotted to guide the controller-handle, a bodily-removable switch-plug included in the motor-circuit, and a seat provided for said switch-plug in said housing adjacent to said handle, substantially as described.

Specification signed and witnessed this 8th day of March, A. D. 1905.

VICTOR E. CHAMBERLIN.
